CLAIM

The ornamental design for a cookware side handle, as shown and described.

DESCRIPTION

FIG. 1 is a perspective view from above of the 1st embodiment of the “cookware side handle”, showing my new design;

FIG. 2 is a top plan view of the 1st embodiment thereof;

FIG. 3 is a front elevation view of the 1st embodiment thereof;

FIG. 4 is a side elevation view of the 1st embodiment thereof;

FIG. 5 is a bottom plan view of the 1st embodiment thereof;

FIG. 6 is a back elevation view of the 1st embodiment thereof;

FIG. 7 is a perspective view from below of the 1st embodiment thereof;

FIG. 8 is a perspective view from above of the 2nd embodiment thereof;

FIG. 9 is a top plan view of the 2nd embodiment thereof;

FIG. 10 is a front elevation view of the 2nd embodiment thereof;

FIG. 11 is a side elevation view of the 2nd embodiment thereof;

FIG. 12 is a bottom plan view of the 2nd embodiment thereof;

FIG. 13 is a back elevation view of the 2nd embodiment thereof; and,

FIG. 14 is a perspective view from below of the 2nd embodiment.
